HARD SURFACE FLOOR COVERING OR SIMILAR ARTICLE

Harvey G. Cohen, Bloomfield, and Harry A. Shortway,
Glen Rock, N.J., assignors to Congoleum-Nairn Inc.,
Kearny, N.J., a corporation of New York

Filed Nov. 30, 1959, Ser. No. 58,510

Term of patent 14 years

(Cl. D92—17)

The figure is a plan view of a hard surface floor covering showing our new design.

A full width is shown between the horizontal edges and a horizontally repeating unit is enclosed within the vertical broken lines.

We claim:

The ornamental design for a hard surface floor covering or similar article, substantially as shown and described.
